SAFETY RAZOR

Jay T. Hellmann, Chicago, Ill.

Application August 28, 1944, Serial No. 551,523

5 Claims. (Cl. 30—41)

1

My invention relates to safety razors, having among its objects and advantages the provision of an improved razor structure to provide arrangements and facilities for: (1) clamp pressure on the blade to be applied heavily from the guard side of the blade, and at very close proximity to the cutting edge of the razor blade; (2) for quick and easy placement of the razor blade in the razor and the removal of the same therefrom; (3) for rapidly opening and closing the razor; and, (4) for suspending the razor blade in a separated anchored position for drying of the blade and other parts of the razor.

In the accompanying drawings:

Figure 1 is a tilted side view of the razor blade guard and the tubular stem.

Figure 2 is a sectional end view of the razor blade guard and the tubular stem, broken apart in midsection.

Figure 3 is a side view of the razor operating member.

Figure 4 is a sectional side view of the razor operating member.

Figure 5 is a side view of the abutment member.

Figure 6 is an elevational side view of the razor clamp member.

Figure 7 is an elevational end view of the razor clamp member.

Figure 8 is a fragmentary transverse section view of the razor clamp member, with lower end broken away.

Figures 9, 10 and 11 are side views of the razor in elevation.

Figure 12 is a sectional side view of the razor.

In the embodiment of the invention selected for illustration, I make use of a guard and blade support 13, Figure 1.

The guard 13 having an upper concave side and a lower convex side is provided with notched edges 14, Figure 1. Notched edges 14 are provided with bevelled ledges 15—15, Figures 1 and 2. Bevelled ledges 15—15 are located on the upper side of the notched edges 14 and extend crosswise of the notched edges 14. Beveled ledges 15—15 are positioned on the notched edges 14 in alignment with each other, giving the effect of a straightaway ledge element which is employed to contact razor blade from guard side of the razor and very near to the cutting edge of the razor blade. The guard 13 is provided with

two hooked lugs 16—16, Figure 1. The hooked lugs 16—16 are fixedly attached to the guard 13, said hooked lugs being located one at either end of the guard 13. The hooked lugs 16—16 are of flat shape and of proper thickness to permit sliding entrance of the hooked lugs 16—16 into the narrow slot of a suitable safety razor blade. The hook ends 18—18 of the hooked lugs 16—16 are positioned to extend in opposite directions, one to the other.

The guard 13 is provided with usual round opening 20, Figure 1. The guard is provided with two notches 22—22, located one at either side of the round opening 20 of the guard 13.

15 A tubular stem 24, Figures 1 and 2, is provided. Tubular stem 24 is fixedly attached by its upper end to the convex side of the guard 13. Said tubular stem 24 is provided with two oppositely positioned channels 25—25, Figures 1, 2 and 12.

20 Slotted channels 25—25 are arranged inside the tubular stem 24 and extend longitudinally therein. Channels 25—25 are so positioned in the tubular stem 24 as to be aligned with the notched openings 22—22, Figure 1. Tubular stem 24 is provided with a stepped bore 27, Figure 2. Diameter of the bore 27 in that part of the bore next the guard 13, is reduced. Left hand threading is provided in the intermediate part of the bore 27. The lower end of the tubular stem 24 is provided with a lipped edge 26, Figures 1, 2, 9, 10 and 11.

An operating member, Figures 3 and 4, is provided. The operating member comprises a cylindrical body having a small upper cylindrical portion 31, and a large intermediate cylindrical portion 33, and a lower knob 34. The small cylindrical portion 31 is provided with right hand threading 30, and the large cylindrical portion 33 is provided with left hand threading 32. The cylindrical body is provided with a bore 35, said bore 35 extending longitudinally into the cylindrical body, through the knob-end thereof. The bore 35 is intersected at one side by an oblong square opening 36, said oblong square opening 36 being cut into the side of the cylindrical body portion 33 thereof.

An abutment member, Figure 5, is provided. The abutment member comprises a cylindrical body 37; a flat spring 38, and an oblong square shaped body 39. The cylindrical body 37 is at-

tached by one of its ends to one end of the flat spring 38, and the oblong square shaped body 39 is attached by one of its ends to the other end of the flat spring 38.

A blade clamp member, Figures 6, 7 and 8, is provided. Blade clamp member comprises a clamp plate 40, and a cylindrical body 41, said cylindrical body 41 having one of its ends fixedly attached to the clamp plate 40. Clamp plate 40 is provided with two rectangular openings 42-42, Figures 6 and 12. Cylindrical body 41 is provided with two flanges 43-43, said flanges 43-43 being formed on the cylindrical body 41, located on opposite sides thereof, and extending longitudinally therewith. The flanges 43-43 are provided with ovalled enlarged portions 44-44, Figures 6, 7 and 12. The unattached end of the cylindrical body 41 is provided with an inner bore 45, Figure 8, said bore 45 being provided with right hand threading.

Connected relationship of the members is effected by entering abutment block member, Figure 5, into the bore 35 of the operating member, Figure 4, and entering the operating member into the bore 27 of the tubular stem 24 Figure 1; pressing abutment block 39 down, and turning the knob 34 to left. The razor is then in position to be connected in operational relationship with the blade clamp member, with the operating member, in full projected position, ready to receive the razor blade, which may be slidably placed over the hooked lugs 18-18, Figure 1. When the blade has been placed over the hooked lugs 18-18, the blade clamp member, Figure 6, is entered through the round opening of the razor blade and into the bore 27 through the round opening 28 of the guard 13 when the razor is in position of Figures 11 and 12. The knob 34 may then be turned to the right thereby connecting the blade clamping member to the operating member, as shown in Figure 12 with the threaded portion 39 entering the threaded bore 45 of the cylindrical body 41, thus drawing the clamping member downward upon the guard of the razor into full clamped position, as in Figure 9.

In position of Figure 9 razor is ready for use. After using, razor is released from clamped position as in Figure 9 by turning the knob 34 to the left which drives the operating member in direction of the guard 13, and drives the clamp plate member in direction away from the guard 13; ovalled enlarged portions 44-44 of the flanges 43-43 contact the edges of the razor blade in the narrow slot of the razor blade, and the razor blade is carried in direction away from the guard 13 until it abuts the hooks 18-18 of the hooked lugs 18-18, and simultaneously with these movements the abutment block 39 arrives at and abuts the lip on the edge 26 of the tubular stem 24. The razor is then in anchored suspended position as in Figure 10, ready for putting away to dry. When desired to use again, the clamping member is drawn to the clamped position of Figure 9 by turning the knob 34 to the right. When desired to change the blade or to disconnect the parts of the razor the clamp member is raised to the position of Figures 11 and 12 by pressing down the abutment block 39 and turning the knob 34 to the left until the clamping member is disconnected from the operating member.

The distance between the ends of the hooks 18-18 of the hooked lugs 18-18, Figure 1, is of proper length to allow the razor blade to be placed over the hooked lugs by first placing one end of the blade over one of the hooked lugs and then

by longitudinal displacement past the center which then permits the opposite end of the blade to be placed over the other hooked lug, and the entrance of the end of the tubular body 41 through the round opening of the razor blade into the round opening 28 of the guard 13, serves to centrally position the razor blade over the hooked lugs 18-18 as to cause the ends of the razor blade at the ends of the narrow slot in the razor blade to abut the hooks 18-18, and not allow the razor blade to pass the hooks 18-18 until after the clamp plate member is removed from the razor when the blade is released for passage of the hooks 18-18 and the blade may be easily lifted from off of the hooked lugs 18-18. When the razor is in position of Figures 11 and 12 the clamp plate member may be lifted out of the razor and the razor disconnected by turning the knob 34 to the right.

Employment of right-left hand screw operative arrangement in the razor structure provides means for retention of the operating member in connected operational relationship with the tubular stem and the blade guard and the blade clamp member; at same time providing a razor structure that may be easily disconnected if and when desired. The right-left hand screw arrangement also provides mean for greatly accelerating the operating facility of the razor.

Without further elaboration, the foregoing will so fully explain my invention, that others may, by applying current knowledge, readily adapt the same for use under various conditions of service.

I claim:

- 35 1. A safety razor guard having notched edges, two upright diametrically opposed hooked lugs fixedly attached to the razor guard, bevelled ledges formed on the upper side of said notched edges of the razor guard, said bevelled ledges 40 extending lengthwise of the notched edges of the razor guard, a round central opening in the razor guard having two notches communicating therewith, one extending out from each side thereof.
- 45 2. In a razor handle, a tubular stem having two channels located in the inner wall of said stem, said channels extending longitudinally from one end of said stem, left hand threading in the bore of said stem and a lipped edge on the other end of said stem.
- 55 3. A razor including the handle described in claim 2 wherein there is provided a safety razor guard having a concave upper side an a lower convex side to which one end of said stem is fixedly attached at the center thereof.
- 65 4. A safety razor operating member, comprising a cylindrical body having a cylindrical portion of small diameter, and a cylindrical portion of large diameter, an elongated shoulder formed on said body intermediate of said large and said small cylindrical portions, right-hand threading on said small cylindrical portion and left-hand threading on said large cylindrical portion and a longitudinal bore into that portion of the cylindrical body having the large diameter, and a rectangular opening through the side of said cylindrical body intersecting the longitudinal bore into the cylindrical body.

- 70 5. A safety razor clamp member comprising a clamp plate and a cylindrical body formed at the medial point of said clamp plate on the under-surface thereof, said clamp plate having two rectangular openings located one at either end of the clamp plate and the affixed cylinder body having two flanges formed on the sides

thereof, each of said two flanges having an intermediate oval and large portion, and aforesaid cylindrical body having a longitudinal inner bore, said longitudinal inner bore having right-hand threading.
